(57) **CLAIM**

I claim the ornamental design for an ejection station, as shown and described.

DESCRIPTION

FIG. 1 is a front perspective view of an ejection station showing my new design;

FIG. 2 is a right elevation view thereof;

FIG. 3 is a left elevation view thereof;

FIG. 4 is a front elevation view thereof;

FIG. 5 is a rear elevation view thereof; and,

FIG. 6 is a top plan view thereof.
